ATTORNEY

INVENTOR

UNITED STATES PATENT OFFICE.

NON H. BROWN, OF DETROIT, MICHIGAN.

STEAM INJECTOR FOR FURNACES.

Application filed May 22, 1925. Serial No. 32,234.

To all whom it may concern:

Be it known that I, NON H. BROWN, a citizen of the United States, and residing at Detroit, county of Wayne, State of Michigan, have invented a new and Improved Steam Injector for Furnaces, of which the following is a specification.

This invention relates to furnace attachments, and relates particularly to attachments to furnaces for the purpose of injecting steam to induce a more complete combustion of fuel and to substantially prevent the formation of smoke.

It is the object of the invention to provide a steam injector of the described character that will act to spread steam in the form of a blanket or stratum above the fire.

Another object is to form such a stratum of steam by discharging the steam in the form of angularly intersecting jets.

These and various other objects will be apparent from the following description wherein reference is made to the accompanying drawings illustrating a preferred embodiment of my invention.

Figure 1 is a view in sectional elevation of a steam boiler equipped with the improved device.

Figure 2 is a detail plan view of the injector.

Figure 3 is an enlarged side view of the same.

Figure 4 is an enlarged plan view of one of the branches of the jet of the injector.

In these views, the reference character 1 designates a boiler, the upper portion of which is tapped by the usual pipe 2 for delivering steam from said boiler to any desired point. For heating said boiler, there is provided a fire-box 3, equipped with the usual grate 4. The present invention consists in connecting to the pipe 2 or to any other source of steam supply, a pipe 5 controlled by a valve 6 and having a portion 5^a projecting into the fire-box through the front wall of the boiler, and provided with divergent branches 7, each terminating in a pair of divergent jet nozzles 8, disposed preferably in a common vertical plane. The nozzles 8 of each pair are provided with outlets 9, from which the steam discharges in intersecting jets 10, producing through

their impact a thin blanket or stratum of steam 11, extending horizontally above the fire. The products of combustion as they rise from the burning fuel encounter this steam blanket, and the resultant moistening of any solid particles carried in suspension by said gases so increases the weight of said particles that they fall back into the fire 60 where they are fully consumed.

Thus the construction serves at the same time to effect a complete combustion of fuel and to avoid the formation of smoke.

The described injector is particularly desirable for its purpose because in a very simple manner it produces a thin blanket of steam fully above the fire such as to encounter substantially all of the rising combustion gases, and release from the latter 70 suspended solid particles.

From the foregoing description it becomes evident that the device is efficient in operation, and provides a device which accomplishes the objects described.

While it will be apparent that the illustrated embodiment of my invention herein disclosed is well calculated to adequately fulfill the objects and advantages primarily stated, it is to be understood that the invention is susceptible to variations, modifications and change within the spirit and scope of the subjoined claims.

Having thus described my invention, I claim:

1. A steam injector for furnaces comprising a pair of discharge pipes branching in a horizontal plane, and a pair of jet nozzles terminating each of said discharge pipes and diverging in a substantially vertical plane, and having outlets, the directions of which are convergent.

2. A steam injector for furnaces comprising a pair of branching discharge pipes, a pair of jet nozzles terminating each discharge pipe, and diverging transversely to the plane of said discharge pipes, and having outlets opening in convergent directions each pair of said nozzles converging toward the other pair at an acute angle.

In witness whereof I hereunto set my hand,

NON H. BROWN.
